US00D780202S

(12) **United States Design Patent** (10) Patent No.: **US D780,202 S**
Bradbury et al. (45) Date of Patent: **** Feb. 28, 2017**

**(54) DISPLAY SCREEN OR PORTION THEREOF
WITH GRAPHICAL USER INTERFACE**

(71) Applicant: **Oracle International Corporation**
Redwood Shores, CA (US)

(72) Inventors: **Josefina Maria Bradbury**, San Francisco, CA (US); **Soraya Younossi**, Burlingame, CA (US); **Daniel Frank Lewis**, Port Moody (CA); **Michael F. Mohageg**, Los Altos, CA (US)

(73) Assignee: **Oracle International Corporation**,
Redwood Shores, CA (US)

(**) Term: 14 Years

(21) Appl. No.: 29/503,593

(22) Filed: Sep. 26, 2014

(51) LOC (10) Cl. 14-04

(52) U.S. Cl.

USPC D14/486

CLAIM

The ornamental design for the display screen or portion thereof with graphical user interface, as shown and described.

DESCRIPTION

FIG. 1 a front view of a display screen or portion thereof with graphical user interface showing our new design; and, FIG. 2 is an alternative embodiment thereof.

The broken line showing of the display screen or portion thereof is included for the purpose of illustrating environment structure and forms no part of the claimed design. ORACLE is a registered trademark of Oracle International Corporation.
